UNITED STATES PATENT OFFICE

CHARLES WILLIAM ABREE COMLEY, OF LONDON, ENGLAND, ASSIGNOR TO COMLEY AUTOMATIC TICKETS LIMITED, OF LONDON, ENGLAND, A BRITISH COMPANY

TICKET ISSUING APPARATUS

Application filed July 13, 1929, Serial No. 378,028, and in Great Britain July 17, 1928.

This invention is for improvements in or relating to ticket-issuing apparatus of the type wherein intermittently-actuated feed mechanism having an operating member, 5 such as a lever, serves to feed a ticket strip to the punching mechanism. Such apparatus is usually provided with counting mechanism for registering the number of tickets punched and the value of the fares received for the 10 tickets that are issued from the machine, and this invention has for its main object to ensure that the punching mechanism and the counting mechanism associated therewith shall not be operated when no ticket is in the 15 apparatus, or when only the end portion of a ticket strip is left in the machine. The invention is particularly applicable to, and will be described with reference to, ticket-punching apparatus of the kind described 20 in the British patent specification No. 293,883, although it is not restricted thereto.

According to the invention, there is provided in or for ticket-issuing apparatus of the type described, the combination with the 25 feed mechanism or the punching mechanism, or both these mechanisms, of a locking device therefor controlled by the ticket strip, which locking device is normally held inoperative by the strip, but is rendered operative to lock 30 one or both of said mechanisms when the end of the strip leaves it, or when a "mutilated" portion (e. g. end portion) of the strip registers with it.

According to a feature of the invention, a 35 support over one face of which the ticket strip is fed has an aperture normally covered by the strip, and the locking device has a controlling part (e. g. a lever-arm) urged by 40 a spring to move through said aperture towards the strip and thereby lock the feed mechanism, which device is held unlocked when said controlling part is prevented by the strip from extending through the aperture beyond the face of the support over 45 which the strip is fed.

According to another feature of the invention, the locking device is arranged to lock and unlock the operating member of the feed 50 mechanism, or of the punching mechanism,

or an operating member common to both these mechanisms.

The invention further provides for use with a ticket-issuing apparatus comprising the locking device described above, a ticket strip whereof a portion (e. g. an end portion) is so mutilated (e. g. slotted or otherwise apertured) or otherwise prepared (e. g. weakened) that when it registers with the locking device the latter will operate to lock 55 the feed mechanism or the punching mechanism or both these mechanisms.

The invention also provides a specific construction of ticket-strip-controlled locking device for use in ticket-issuing apparatus, 60 and a specific construction of ticket-strip for controlling the locking device.

It is to be understood that the terms "punching" and "ticket-punching" used herein include printing, impressing or otherwise marking a ticket as for cancelling it.

The invention is diagrammatically illustrated, by way of example, in the accompanying drawings, wherein:

Figures 1 and 2 are end elevations showing 75 one construction of locking device according to the invention in its inoperative and operative position, respectively, and

Figure 3 shows the end portion of a ticket-strip that controls the locking device. 80

Like reference characters designate like parts in all the views.

Referring to the drawings, which illustrate the invention as applied to feed mechanism and punching mechanism in ticket-punching 85 apparatus of the kind described in the said specification No. 293,883, an annulus 10 having at one edge a flange 11 is fixed on the frame of the apparatus so as to lie close beside a rotary feed member in the form of a drum or sprocket wheel, not shown, for feeding a ticket-strip 12 to the punching mechanism. The annulus 10 is of the same diameter as the sprocket wheel, whereof the axis of rotation extends through the centre of the 90 annulus, and the ticket-strip, which has holes 13 for engagement by the sprockets of the feed member, lies partly on the latter and partly on the annulus, with one edge close to the flange 11. The ticket-strip lies on only 95 100

a part, e. g. about half of the annular support, which part constitutes an arcuate support for the strip and has an aperture 14 in its face normally covered by the strip. This aperture is preferably rectangular, but may be round or of any other convenient shape.

An operating member 15, 16 of the feed mechanism and punching mechanism is in the form of a pivoted lever fulcrumed at 17 on the base plate of the machine, and has a stop 18 in the form of a notch in a boss 19 on the lever. The arm 15 lies alongside a handle member 20 at a convenient distance away from it so that when these two members are gripped by one hand and the arm 15 is caused to approach the handle member 20 the lever 15, 16 will be rocked to operate the machine.

The locking device aforesaid has the form of a spring-controlled double-ended lever 21, whereof one end 22, which may be rounded or may carry an anti-friction member, is arranged to enter the aperture 14 and co-act with the strip 12, and the other end 23 is formed as a catch and is arranged to move into and out of engagement with the notch 18. When the apparatus is loaded and the ticket-strip 12 is being fed to the punching mechanism the end 23 of the lever 21 controlled by a spring 121 is held out of engagement with the operating lever 15, 16, as shown in Figure 1, so that this lever can be rocked to operate the machine. When the ticket strip is completely unwound from its spool and uncovers the aperture 14, the catch 23 will snap into the notch 18 when the members 15, 20 have been pressed together, as shown in Figure 2, and will lock the operating member and prevent the machine from being worked.

Instead of locking the operating member 15, 16 directly, it may be locked indirectly. For example, a spring-controlled catch 25, 26 such as is usually associated with the operating member and has a handle member 25 extending alongside the fixed handle portion 20 of the apparatus, has its bent arm 26 arranged to lock the operating member by entering a notch 27 in the boss 19. The locking device 21 may be arranged to control this catch 25, 26, for example by co-acting with a stop, such as a notch, provided on it, and hold it against rocking movement in a manner similar to that described above.

The operating member 15, 16 may be operatively connected with the feed mechanism, not shown, and the punching mechanism, not shown, by a link 28 and a reciprocating member 29, so that the operating member 15, 16 may be considered to constitute a part of each of these mechanisms.

As the feed drum of the ticket strip may be placed a short distance away from the punching mechanism, one or more tickets may be in the machine after the end of the ticket-strip has uncovered the aperture 14. In this

case it is desirable to lock the apparatus against further operation before the last ticket or two tickets in the machine have been punched. For this purpose, as shown in Figure 3, the end of the ticket strip may be provided with a slot, such as 30, or may be otherwise apertured or prepared, for example weakened, so that the locking device will operate when this portion or slot registers with the aperture 14.

As illustrated, the last two tickets are left blank, the slot 30 being in the very last ticket, and the third last ticket being printed, as shown, to provide thereon various designations of fares, stages and classes, these designations being arranged in three parallel rows extending in the direction of length of the strip, the classes being in the middle, and the fares and stages at the two sides. This ticket is thus adapted for use with an arrangement of punches as described in the co-pending British patent application No. 20,714/28. Alternatively, instead of leaving the last two or three tickets blank, they may be printed, as just described, and marked "cancelled" before the strip is inserted into the machine. Further, the aperture in the strip, instead of being a slot 30, may open through one side of the ticket-strip, e. g. that side which lies nearest to the flange 11, and may have the form of a recess. The invention thus provides not only a locking device controlled by the ticket strip, but also an improved construction of ticket-strip for controlling the locking device.

The invention ensures that the punching mechanism cannot be operated and counters associated therewith will not be actuated to indicate either the issuance of a ticket or the receipt of a fare, unless a ticket is actually present in the machine and is actually punched, whereby the accuracy of the readings of the counting mechanism associated with the apparatus is enhanced.

Various modifications may be made in the details of construction described above without departing from the invention.

I claim.

1. In a ticket-issuing apparatus, the combination of a ticket strip, feed mechanism therefor comprising a reciprocatory operating member and a locking device for positively locking said operating member, which locking device is normally held inoperative by the strip, but when released by the latter is operative to lock said operating member at that end of its stroke from which it returns to its rest position.

2. In ticket-issuing apparatus, the combination of a ticket strip, mechanism associated therewith, an operating member for the latter in the form of a pivoted lever having a circular boss rotatable about its fulcrum from a normal or rest end position to a second end position, which boss has a

notch in its periphery, and a locking lever, whereof one end is arranged to move into and out of engagement with said notch when the lever is located in its second end position, a
5 spring tending to hold the locking lever in locking engagement with said notch for positively locking said operating member, the other end of which locking lever is arranged to co-act with said strip and render the locking lever inoperative by holding the first said end out of engagement with said notch.
10

In testimony whereof I affix my signature.

CHARLES WILLIAM ABREE COMLEY.
